CLAIM

The ornamental design for an automated food frying machine, as shown and described.

DESCRIPTION

FIG. 1 is a front elevational view of an automated food frying machine showing our new design;

FIG. 2 is a right side elevational view thereof;

FIG. 3 is a left side elevational view thereof;

FIG. 4 is a perspective view thereof;

FIG. 5 is a top plan view thereof; and,

FIG. 6 is a rear elevational view thereof.

The undisclosed bottom view is plain and unornamented.

*Fig. 1**Fig. 2**Fig. 3**Fig. 4**Fig. 5**Fig. 6*
